UNITED STATES PATENT OFFICE.

ERNEST H. STUETS, OF PHILADELPHIA, PENNSYLVANIA.

GAS-LIGHTER.

1,153,969.

Specification of Letters Patent. Patented Sept. 21, 1915.

Application filed October 27, 1914. Serial No. 868,833.

To all whom it may concern:

Be it known that I, ERNEST H. STUETS, a citizen of the United States, residing at Philadelphia, in the county of Philadelphia 5 and State of Pennsylvania, have invented certain new and useful Improvements in Gas-Lighters, of which the following is a specification.

My invention relates to improvements in 10 gas lighters, the object of the invention being to provide improved means for turning on and off the gas supply from a burner, and at the same time automatically controlling the operation of the pilot light, so that 15 when the gas is turned on, the pilot light will be permitted a supply of gas sufficient to insure the lighting of the burner, whereas under normal conditions the pilot light is maintained low.

20 A further object is to provide improvements of the character stated which are especially adapted for use in connection with water heaters, and which automatically turns off the gas when the temperature of the 25 water reaches a pre-determined degree.

A further object is to provide improvements of the character stated which are operated electrically from a distance, and which is of extremely simple construction, 30 strong and durable in use.

With these and other objects in view, the invention consists in certain novel features of construction and combinations and arrangements of parts as will be more fully 35 hereinafter described and pointed out in the claims.

In the accompanying drawings: Figure 1 is a view partly in elevation and partly in section illustrating my improvements. Fig. 49 2 is a view partly in elevation and partly in vertical section. Fig. 3 is a view in transverse section on the line 3—3 of Fig. 2. Fig. 4 is a view in vertical section through the magnet inclosing casing and the gas 45 supply pipe showing parts within the casing in elevation. Fig. 5 is an enlarged view in longitudinal section through the pilot controlling valve. Fig. 6 is a view in transverse section on the line 6—6 of Fig. 5. Fig. 7 is a view in transverse section on the 50 line 7—7 of Fig. 4. Fig. 8 is an electric diagram.

1 represents a water chamber that I shall term a "boiler," as its function is to contain 55 water adapted to be heated and utilized for ordinary household or other purposes.

2 is a coil through which water is supplied to the boiler, and it is to be understood that any suitable construction of boiler may be used as my invention is not limited to any particular type of boiler.

3 is a gas burner having a central opening 4 therein, and supported at the upper end of a gas supply pipe 5, the latter located at one side of the center of the burner, and at its lower end flared outwardly as shown at 6 so as to provide ample space for the entrance of air. In other words, the burner above described is of the ordinary Bunsen type, and is connected to a gas supply pipe 7 by means of an electro-magnet inclosing casing 8, and a cock 9. In the casing 8, a central vertical pipe 10 having a turning plug 11 therein is located, and at the ends of said pipe 6, disks 12 and 13 respectively 75 are secured, and over which casing 8 is positioned, and is made removable so that access may be readily had to the interior thereof.

The turning plug 11 has secured thereto a segmental disk 14, the latter recessed at one 80 edge as shown at 15, and into which recess a pin 16 is projected to limit the turning movement of the plug. The segmental disk 14 is engaged by two pivoted armatures 17 and 18 respectively.

The armatures 17 and 18 have parallel lugs 19 projecting therefrom at their centers and located at opposite sides of hangers 20 depending from the upper disk 12. Manually operated pulls 21 project through 90 the upper disk 12, and are connected to fingers 19 of the respective armatures to permit the armatures to be moved and the gas to be manually turned on and off as occasion may require.

95 The armatures 17 and 18 are located above electro-magnets L and O respectively, the former causing the gas to be turned on to light the burner, and the latter causing the gas to be turned off to extinguish the burner.

100 It will be noted that the movement of one armature compels the reverse movement of the other, and these parts are of such a construction that when once moved they will remain in the position moved until 105 the other magnet is energized to reverse the positions.

22 represents a relatively small gas tube 110 communicating with the pipe 10 below the turning plug 11. The tube 22 extends up beside pipe 5, and at its upper end is provided with a chimney 23 in which a small

pilot light is constantly burning. The tube 22 is provided between its ends just above the disk 12 with an elbow 24, and through the bottom of this elbow, a stem 25 of a valve 26 projects. The valve 26 controls the supply of gas to the pilot, a small quantity of gas being permitted to pass through a groove 27.

The valve 26 is normally held on its seat 10 by a spring 28, and when the valve is opened, a relatively large amount of gas is supplied to the pilot to allow the same to burn above the chimney as will be hereinafter explained.

The lower end of the stem 25 is positioned 15 above a head 30 on the upper end of a vertically movable rod 29. The lower end of this rod 29 is positioned above a pivoted armature 31 controlled by an electro-magnet P, so that when the magnet P is energized, 20 the armature 31 will compel the valve 26 to open, and allow a sufficient amount of gas to flow through the tube 22 to project the flame of the pilot above the chimney 23 and through the opening 4 in the burner 3, causing 25 the burner to be lighted.

To insure a spreading of the flame and the proper lighting of the burner, a V-shaped deflecting bar 32 is positioned across the opening 4 and serves to deflect the flame 30 to both sides in position to ignite the gas escaping through the orifices of the burner.

The boiler 1 is equipped with a thermostat 33 which may be made in any approved form, but in the present instance consists of 35 a tube inclosing a rod 34, the tube and rod being of different metals, so that the expansion of the tube causes the longitudinal movement of the rod. The outer end of the rod is connected to a lever 35, the latter 40 pivotally supported on a bracket 36. The lever 35 carries at its free end, a contact 37 normally spaced from a contact 38, the latter insulated from the boiler.

On the upper disk 12, I locate a support 45 39 carrying a contact 40 insulated therefrom. On one of the manually operated pulls 21, I locate a contact 41 which engages the contact 40 when the armature 17 is in position to turn on the gas, and these contacts are apart when the armature 17 is elevated by reason of the downward movement 50 of armature 18 to shut off the gas.

In Fig. 8, I illustrate an electric diagram showing one means for electrically controlling the several parts. L' and O' represent 55 electric switches which preferably comprise spring-pressed buttons, so that when the buttons are pressed, the circuit will be closed, and when released, the circuit will be opened. B represents a battery or source of electricity supply which is connected in circuit with the several electro-magnets and contacts as will now be explained. From one 60 side of the battery B, a wire 42 extends to the switches B' and L'. A wire 43 connects

switch L' with electro-magnet L, which latter is connected to electro-magnet P by a wire 44, and the latter is connected to the opposite side of the battery by a wire 45. Switch O' is connected by a wire 46 with the electro-magnet O, and the latter is connected by a wire 47 with wire 45. 48 is a wire connecting the contact 37 with the wire 42, and 49 is a wire connecting contact 38 with contact 40, contact 41 being connected 75 by a wire 50 with wire 46.

When the switch L' is operated, the circuit is as follows: from battery B, through wire 42, switch L', wire 43, electro-magnet L, wire 44, electro-magnet P, and wire 45 back to the battery. This causes the gas to be turned on and the pilot light to flare up sufficient to light the burner. It is to be understood that as soon as the circuit above described is broken, the valve of the pilot light returns to closed position, so that the pilot assumes its normally small flame. The energizing of electro-magnet L moves the contact 41 against the contact 40. When it is desired to turn off the gas supply to the burner, switch O' is operated. The electric circuit is then from battery B, through wire 42, switch O', wire 46, electro-magnet O, wire 47, and wire 45 back to the battery. If the switch O' is not operated to cut off the supply of gas, and the temperature of the water in the boiler reaches a pre-determined degree, the operation of the thermostat 33 will cause the contact 37 to move against contact 38, and close the electric circuit to the magnet O as follows:—from battery B, through wire 42, wire 48, contact 37, contact 38, wire 49, contact 40, contact 41, wire 50, and wire 46 to electro-magnet O, and from the latter through wire 47 and wire 45 to the battery. The electro-magnet O will then turn off the gas, and in doing so will compel the armatures 17 and 18 to reverse their former positions. The movement of armature 17 will instantly separate the contacts 40 and 41, so that there will be no drain upon the battery. It will therefore be noted that the contacts 40 and 41 are together only when the gas is turned on, and at such times the contacts 37 and 38 are apart, so that there is no drain upon the battery at any time.

Various slight changes might be made in the general form and arrangement of parts described without departing from my invention, and hence I do not limit myself to the precise details set forth, but consider myself at liberty to make such changes and alterations as fairly fall within the spirit and scope of the appended claims.

Having thus described my invention, what I claim as new and desire to secure by Letters Patent is:

1. The combination with a boiler to be heated, a burner for heating the same, a gas

- supply pipe communicating with the burner, a pilot tube communicating with the gas supply pipe, a valve in the pilot tube, a valve in the gas supply pipe, two electro-
5 magnets controlling the movement of the last-mentioned valve, an electro-magnet controlling the movement of the valve in the pilot tube and connected in circuit with one of said first-mentioned magnets, a thermostat on the boiler controlling contacts normally apart, said contacts included in an electric circuit with the magnets, whereby the valve in the gas supply pipe is closed by the action of one of the first-mentioned magnets when the temperature of the water in the boiler reaches a pre-determined degree, substantially as described.
2. The combination with a boiler to be heated, a main burner for heating the same, 20 having an opening therein, a gas supply pipe communicating with the burner, a pilot tube communicating with the gas supply pipe and terminating below the opening in the main burner, a valve in the gas supply pipe, a valve in the pilot tube past which a small amount of gas is permitted to flow when the valve is closed, a segment on the first-mentioned valve, two electro-magnets, pivoted armatures moved by the electro-magnets and engaging the segment, one of said electro-magnets adapted to move the valve to open 25 position, and the other to move the valve to closed position, manually operated pulls connected to the armature, an electro-magnet controlling the movement of the valve in the pilot tube and connected in circuit with one of said first-mentioned magnets, a thermostat on the boiler controlling electric contacts normally apart, electric contacts controlled by one of said pulls and together when the gas supply valve is open, said last-
30 mentioned contacts in circuit with the contacts controlled by the thermostat, and in circuit with the magnet for turning the first-mentioned valve to closed position, and electric switches included in electric circuits 35 with the first-mentioned electro-magnets, substantially as described.
3. The combination with a boiler to be heated, a main burner for heating the same, 40 having an opening therein, a gas supply pipe communicating with the burner, a pilot tube communicating with the gas supply pipe and terminating below the opening in the main burner, a valve in the gas supply pipe, a valve in the pilot tube past which a small amount of gas is permitted to flow when the valve is closed, a segment on the first-mentioned valve, two electro-magnets, pivoted armatures moved by the electro-magnets and engaging the segment, one of said electro-magnets adapted to move the valve to open 45 position, and the other to move the valve to closed position, manually operated pulls connected to the armature, an electro-magnet controlling the movement of the valve in the pilot tube and connected in circuit with one of said first-mentioned magnets, a thermostat on the boiler controlling electric contacts normally apart, electric contacts controlled by one of said pulls and together when the gas supply valve is open, said last-
45 mentioned contacts in circuit with the contacts controlled by the thermostat, and in circuit with the magnet for turning the first-mentioned valve to closed position, and electric switches included in electric circuits 50 with the first-mentioned electro-magnets, substantially as described.
- In testimony whereof I have signed my name to this specification in the presence of two subscribing witnesses.
